US00D928328S

(12) **United States Design Patent** (10) Patent No.: **US D928,328 S**
(45) Date of Patent: **** Aug. 17, 2021**

(54) **CONTROL PANEL**

(71) Applicant: **GEBRUEDER MARTIN GMBH & CO. KG**, Tuttlingen (DE)

(72) Inventors: **Sven Zehnder**, Aichhalden (DE); **Hans Georg Kloster**, Tuebingen (DE); **Sebastian Rieger**, Stuttgart (DE)

(73) Assignee: **GEBRUEDER MARTIN GMBH & CO. KG**, Tuttlingen (DE)

(**) Term: **15 Years**

(21) Appl. No.: **29/717,479**

(22) Filed: **Dec. 17, 2019**

(30) **Foreign Application Priority Data**

Jun. 17, 2019 (EP) 006582680

(51) LOC (13) Cl. **24-02**

(52) U.S. Cl.

USPC **D24/185**

(58) **Field of Classification Search**

USPC D3/203.1, 203.2, 203.3; D6/332, 641, D6/642, 643, 643.1, 644, 645, 646, 647, D6/649, 650, 650.1, 655, 655.1, 655.11, D6/655.12, 655.13, 655.14, 655.15, D6/655.16, 655.17, 655.18, 655.19, 655.2, D6/655.21, 655.22, 655.23, 698, 700, D6/701, 553, 559, 561, 563; D10/40; D13/101, 112, 114, 118, 120, 121, 122; D14/300, 301, 302, 307, 313, 314; D15/199; D23/200, 202, 207, 209, 210, D23/499; D24/100, 133, 144, 158, 159, D24/160, 162, 163, 164, 170, 177, 183, D24/184, 185, 186, 187, 216, 217, 227, D24/228, 229, 230, 231, 232, 233, 234; D25/15; D34/12, 14

(57) **CLAIM**

The ornamental design for a control panel, as shown and described.

DESCRIPTION

The sole FIGURE is a perspective view of the control panel according to the claimed design.

The broken lines illustrate portions of the control panel and form no part of the claimed design.

1 Claim, 1 Drawing Sheet
